UNITED STATES PATENT OFFICE

100,080

DESIGN FOR A NEGLIGEE

Sylvia S. Pedlar, New York, N. Y.

Application April 16, 1936, Serial No. 62,150

Term of patent 3½ years

To all whom it may concern:

Be it known that I, Sylvia S. Pedlar, a citizen of the United States of America, residing in Manhattan, county of New York, and State of New York, have invented a new, original, and ornamental Design for a Neglige, of which the following is a specification, reference being had to the accompanying drawing, forming part thereof, wherein,

I claim:

The ornamental design for a neglige, substantially as shown.

SYLVIA S. PEDLAR.
